DISPENSER

Edward J. Ernst, St. Johns, Mich.

Application April 22, 1955, Serial No. 503,222

4 Claims. (Cl. 222—100)

The present invention relates to paste dispensers and is more particularly directed to a new, novel and improved dispenser for toothpaste and the like from collapsible tubes substantially eliminating leakage from the tube when not in use.

Many of the prior art tube dispensers have retained the tube in an inverted position even when not in use. The tube, when in the inverted position, is susceptible to leakage of the paste contents even when pressure squeezing the tube is relieved. In a full tube the weight of the paste tends to cause some leakage from the tube. The normal method for preventing this leakage is by the addition of a spring loaded cap below the mouth of the tube which cap is a part of the dispenser. This means is not entirely satisfactory and always presents sanitation problems since dry caked paste accumulates in the cap and can be a breeding place for bacteria. Another objectionable feature of these prior art caps and dispensers is that the dry cake will build up to such a height that the cap no longer closes the tube mouth and allows leakage and drying within the neck of the tube. Many elaborate mechanical linkages have been devised to insure closure of the mouth of the tube when not in use, but none seem to have overcome the objectionable drying, unhygienic conditions. Prior art dispensers have also lacked simplicity and as a consequence the costs of such structures were generally prohibitive. Many of the prior art dispensers did not provide enclosures for the tube when the tube was not in use.

Therefore, a principal object of the present invention is to provide a paste tube dispenser which will not leak or accidentally discharge the contents of the tube when the tube is not in use.

Another object of the present invention is to provide a paste tube dispenser which has few moving parts, which can be easily fabricated and which is economical to assemble.

Another object of the present invention is to provide a tube paste dispenser for collapsible tubes which is simple in its operational details and hygienic in its structure. A further object of the present invention is to provide a dispenser which may be completely assembled by the purchaser, at home for instance, without the use of elaborate tools.

Another object is to provide a dispenser which closes completely when not in use and which coordinates the opening of the dispenser with the progressive discharge means for the contents.

A still further object is to provide a dispenser which inverts the tube for use, erects the tube when not in use, and the entire control of the structure is accomplished by rotation of a single shaft. These and other objects will become apparent as the description proceeds.

In the drawings:

Figure 1 is a side elevation view of a dispenser for collapsible tubes in accord with the present invention and shows (in phantom line) the pivotal character of the cover outwardly.

2

Figure 2 is a front elevation of the dispenser shown in Figure 1.

Figure 3 is a bottom plan view of the dispenser as shown in Figures 1 and 2 and indicating the open character of the bottom permitting the pivoted cover to swing outwardly on the axis established through the knobs and receptacle and showing the step which limits the pivotal travel of the cover.

Figure 4 is a front elevation of a dispenser in accord with the present invention being fully opened to reveal the positioning of the guideway in the cover closure and the cradle against which the tube (phantom line) reclines when the dispenser is in the closed position.

Figure 5 is an exploded perspective view of the dispenser in accord with the present invention and shows the simple interrelationship of the various members and indicating the ease of assembly.

General description

In general, the paste tube dispenser of the present invention comprises a wall receptacle having a hinged cover which, when open, depends from the lower edge of the receptacle. The pivotal axis for the cover comprises the tube collapsing and winding means and is provided with finger manipulating knobs outside of the receptacle. The hinged cover is provided with rib-like rails on its inner surface forming a guideway to center a collapsible tube therebetween. The receptacle is provided with a cradle to rest the tube against when the cover effects closure of the receptacle and erection of the tube, thus preventing the tube mouth from resting against any of the interior wall surfaces of the receptacle. The receptacle has wall mounting means integral therewith for quick and easy wall mounting. Upon outward rotation of the manipulating knobs the closed receptacle swings open urged by the resulting movement of the tube against the hinged closure and the tube is swung into an inverted exposed position for use. Further rotation of the knobs causes a corresponding downward delivery of material from the mouth of the collapsible tube as the tube is wound on the winding bar. The method of assembly of the dispenser and its component parts is easily accomplished by unskilled persons because all parts are merely slip-fitted to each other. Thus, the dispenser can be shipped and sold in a knock-down condition for assembly by the user.

Specific description

Referring with more particularity to the drawings, a dispenser 11 is provided consisting of a wall receptacle 12 having one side 13 and its bottom 14 open and provided with a pivotally mounted side and bottom cover member 15. The receptacle 12 has a cradle 16 mounted transversely within the interior of the receptacle 12 substantially midway of the length of receptacle 12. The cradle 16 is in a position to receive a collapsible tube 17 (phantom line in Figure 4) thereagainst when the collapsible tube 17 is in an upright position with the cover 15 closed. The receptacle 12 is substantially box-like and the open bottom 14 is provided with a step 18. The step 18 is best illustrated in Figure 3. The receptacle 12 is tapered in the direction of the top 19. The sidewalls 20 converge to the top 19. The cover closure member 15 is provided with guide rails 21 on its inner face 22 running substantially the length of the cover 15 to center the collapsible tube 17 when the cover 15 is in its open position depending from the lower edge of the receptacle 12. The cover closure 15 is pivotally mounted near the lower edge of the receptacle 12, and has its pivotal axis offset outwardly from its tube loaded center of gravity when the tube 17 is in its closed position. This

arrangement assures that the dispenser 11 will be gravity held against opening. The cover 15, best illustrated in Figure 5, is generally J-shaped in side elevation. Barriers 23, molded or otherwise provided in the receptacle 12, serve as stops preventing the cover 15 from entering the receptacle 12 and assure a flush closure. The pivotal axis upon which the cover 15 swings also comprises the axis for the winding and tube collapsing mechanism 24. The winding and tube collapsing mechanism 24 is a bar 25 having an axial slot 26. A pair of finger grasping knobs 27 are provided. The split bar 25 is press fitted at its ends into the knobs 27. An opening 28 mating with the bar 25 is provided in each of the knobs 27. When the ends of the bar 25 are press-fitted into the opening 28 in each knob 27, simple assembly is accomplished, thus keying the bar 25 to the knobs 27. The knobs 27 are each provided with a boss 29. The cylindrical bosses 29 are coaxial with the axis of the knobs 27 and, as will be seen, the knob axis upon assembly coincides with the axis of the bar 25 to form the winding mechanism 24. Each side wall 20 of the receptacle 12 and the cover closure 15 is provided with a clearance hole 30 therethrough, serving as a bearing surface for the bosses 29 and knobs 27, respectively. The slot 26 through the bar 25 is of a width and length to engage the crimped end of the conventional collapsible tube 17. By inserting the crimped end of the tube 17 in the slot 26, the tube 17 may be wound thereover and collapsed thereon to force out the material within the tube 17. The collapsing of the tube 17 occurs when the cover 15 abuts the step 18 and the tube 17 is inverted and centered between the guide rails 21 as shown in Figure 4. The fit of the bosses 29 of the knobs 27 within the bearing surface provided in the closure 15 is such that the cover closure 15 will rotate freely on the bosses 29 when no tube 17 is engaged. When a tube 17 is positioned on the winding mechanism 24 the receptacle 12 may be closed with the tube mouth 31 upward. Outward rotation of the knobs 27 overcomes the rest position of the tube 17 and the cover 15 rotates outwardly carrying the tube 17 as shown in Figure 4. This novel arrangement provides a means for opening and closing the receptacle 12 before and after use. The direction of rotation of the winding means 24 insures the release of extruding pressure on the collapsible tube 17 when the receptacle closure 15 is moved to its closed position.

The rear wall 32 of the receptacle 12 is provided with openings 33 through which screws (not shown) are inserted for providing simple wall mounting means.

It is apparent that modifications may be made in the various elements of the above described embodiment without departing from the spirit or scope of the invention, for example, other wall mounting means well known in the art may be substituted for the specific means indicated. While the slotted bar 25 illustrated is of generally rectangular configuration, it will be appreciated that bars 25 having other forms, for example, bars having cylindrical ends (not illustrated) with flats or keyways may be used as desired. When cylindrical ended bars are used the bar ends are journaled in the openings 28 through the receptacle 12 to directly serve as the cover pivot. When such a modification is employed, then the bosses 29 provided on the knobs 27 are unnecessary.

The dispenser 11 may be manufactured from many types of materials. Some of the more readily available materials are the plastics such as the epoxy resins, phenol-formaldehyde resins, urea-formaldehyde resins, styrenes, the vinyl and copolymers thereof. In particular the form of the structure adapts itself to injection molding with respect to receptacle 12, cover 15, and knobs 27. Metals may be used but are more costly to fabricate and finish and do not generally lend themselves to the tolerances which are held throughout the manufacture of the dispenser 11. Since the dispenser 11 is subject

only to a very small amount of water spray the container may be made from pressed fibre boards coated with waterproof plastics, et cetera.

The operation of the dispenser of the present invention is substantially as follows:

The cover closure member 15 is opened by rotation of the knobs 27 and swings downwardly pivoting about the axis established by the knobs 27 shouldering in the openings 28 through the side walls 20, the receptacle 12 and axially coinciding with the slotted bar 25. The crimped end of a collapsible tube 17 is inserted in the slot 26 of bar 25. The knobs 27 or either of them are rotated to start to wind the tube 17 around the bar 25. The cap of the tube is removed and the dispenser 11 is ready to discharge any desired amount of paste by further outward rotation of the knobs 27. When the desired amount of paste is dispensed the cover closure 15 carrying the tube 17 is rotated into a closed position into and against the receptacle 12. The barrier 23 prevent the cover closure 15 from dropping into the receptacle 12 and the cradle 16 receives the tube 17 preventing the mouth 31 from touching the interior walls thereof. The tube 17 is centered with respect to the cover 15 by the guideway 34 established by the guide rails 21. When it is desired to use the paste again, the knobs 27 are rotated in an outward direction and the cover closure 15 and tube 17 swing downwardly presenting the open end of the tube 17 in a downward position. In the open position the cover 15 rests against the step 18. When the paste has been dispensed the cover 15 is swung closed. The tube 17 is in an upright position when the dispenser is closed thus preventing accidental droppage therefrom and by reason of the location of the tube 17 and cover 15 will not open unless the knobs 27 are rotated over-coming the gravity rest closure. Further, the paste contents cannot be accidentally dispensed inside the receptacle 12 because the direction of rotation of the knobs 27 to expel the paste is outward and such motion will open the cover closure 15 and present the tube 17 in a downward position.

Thus a new and useful dispenser 11 has been provided which can be easily assembled by unskilled persons and which mounts conveniently for wall use.

Other modifications within the skill of the art are intended to be included in the present invention unless such inclusion is negated by the scope of the hereinafter appended claims.

I claim:

1. A dispensing device for collapsible tubes including: a wall receptacle provided with a transverse cradle connecting the side walls; a cover pivotally attached to said receptacle; winding means receiving the crimped end of a collapsible tube and serving as the pivotal axis for said cover; and knobs on the terminal ends of said winding mechanism.

2. A dispensing device for collapsible tubes including: a wall receptacle provided with a transverse cradle connecting the side walls; a cover pivotally attached to said receptacle and having longitudinal guideway thereon for steady and centering a collapsible tube; winding means slotted to receive the crimped end of a collapsible tube and serving as the pivotal axis for said cover; and knobs on the terminal ends of said winding mechanism extending from said receptacle.

3. In a dispensing device substantially as set forth in claim 2, and including a pair of knobs having bosses thereon, said bosses riding in openings in the said receptacle outward from the center of gravity of said cover and pivotal in the said openings through the said receptacle.

4. A dispensing device for collapsible tubes including: a box-like receptacle adapted to be attached to a vertical wall; a transverse cradle for holding erect a collapsible tube and connecting the side walls of said receptacle; a cover provided with spaced apart longitudinal guide rails

on the inner face thereof pivotally attached to said receptacle and opening outwardly from the face of said receptacle; slotted tube winding means on the pivotal axis of said cover and extending through said cover and said receptacle for receiving the crimped end of a collapsible tube; knobs keyed to each end of said winding means

and having bosses journaled by the side walls of said receptacles which knobs, upon rotation, open said cover outwardly and urge the contents from a collapsible tube attached to said winding means.
